UNITED STATES PATENT OFFICE.

CHARLES E. YOUNG, OF FREMONT, WASHINGTON.

ROCK-DRILL.

SPECIFICATION forming part of Letters Patent No. 660,409, dated October 23, 1900.

Application filed March 8, 1900. Serial No. 7,861. (No model.)

To all whom it may concern:

Be it known that I, CHARLES E. YOUNG, a citizen of the United States, residing at Fremont, in the county of King and State of Washington, have invented new and useful Improvements in Rock-Drills, of which the following is a specification.

My invention relates to improvements in rock-drills; and it consists in the peculiar and advantageous construction, certain novel combinations, and the adaptation of parts hereinafter described, and particularly pointed out in the claims appended.

In the accompanying drawings, Figure 1 is a view, partly in longitudinal section and partly in side elevation, of my improved drill. Figs. 2 and 3 are transverse sections taken in the planes indicated by the broken lines 2 2 and 3 3, respectively, of Fig. 1. Fig. 4 is a side elevation of the drill with some of the elements partly broken away. Fig. 5 is a broken plan view. Fig. 6 is a detail broken perspective view illustrating the rectangular frame at the forward end of the drill-carriage and the parts adjacent thereto. Figs. 7, 8, and 9 are detail sections taken in the planes indicated by the broken lines 7 7, 8 8, and 9 9, respectively, of Fig. 4. Fig. 10 is a perspective view of one of the guide-pieces forming part of the drill-rod holder. Fig. 11 is a perspective view of the outer end of the brace or strut. Fig. 12 is a side elevation of a modified form of angle-lever.

The drawings show my improved drill as arranged in a horizontal position; but I desire it distinctly understood that the drill may be arranged vertically, horizontally, or at various angles of inclination, as the conditions may require.

Referring by letter to the said drawings, A is the main support of the drill, which is preferably equipped with one or more adjustable and pointed screws *a*, at one end adapted to engage uneven surfaces and to hold it in its operative position and is also provided at its opposite end with parallel arms *b*, and B is the brace of said support. This brace comprises an outer section *c*, which terminates in a fork *d*, and an inner sleeve-section *e*, which receives the section *c* in a telescopic manner and is provided with a set-screw *f* for engaging the section *c*, whereby it will be seen that

the brace may be readily increased or diminished in length, as occasion demands. The brace-section *e* is equipped at its inner end 55 with a disk *g*, which is provided with a plurality of apertures *h* and is interposed between and pivotally connected to the arms *b* of the support A and is designed to be adjustably fixed to said arms by a removable pin *i*, 60 extending through coincident apertures in the arms and an aperture *h* of the disk, whereby it will be seen that the brace B may be fixed at various angles of inclination to the support A, and said support may be held in 65 various positions to suit different conditions.

C is a carriage which is mounted and adapted to be adjusted on the support A. The said carriage in the preferred embodiment of the invention comprises two collars *j k*, having 70 parallel depending portions *l*; a longitudinal bar *m*, which is designed to bear on the support A and has its ends interposed between and connected to the depending portions *l* of the two collars; a forward rectangular frame 75 *m'*, which has depending portions *m*² disposed at opposite sides of and connected to the forward end of the bar *m*; loops *n*, which receive the support A and have apertured lugs *p*, designed to be arranged coincident with similar 80 lugs *q* on the portions *l* of collar *j* and the portions *m*² of frame *m'*, and longitudinal rods *r*, which are removably arranged in the lugs *p q* of the portions *l m*² and the loops *n* and serve to connect the same. 85

As will be readily observed, when one of the rods *r* is removed the upper portion of the carriage C—that is, the collars *j k*, the bar *m*, and the frame *m'*, together with the drill-rod holder mounted therein—may be easily swung to one side, so as to carry the drill-rod out of the way and permit of the expedited removal of cuttings from the hole that is being drilled. 90

The drill-rod holder in the preferred embodiment of the invention comprises a tubular section D, journaled in the collars *j k* of the carriage and having flanges *s* at its ends, whereby it is held against endwise movement, an endwise-movable section E, arranged to telescope in the section D and having feathers *t*, movable in slots *u* in said section D, whereby it is held against rotation with respect thereto, and a coiled spring G, which

surrounds the section E and is interposed between a collar v thereon and the rear end of section D, whereby it is enabled to return the section E to its normal position subsequent to a blow on the drill-rod. The endwise-movable section E is provided adjacent to its rear end with a collar-flange w, having apertured lugs x at opposite points, and is also provided at its rear end with diametrically-opposite longitudinal slots y. (See Fig. 7.) This slotted portion of the section E is surrounded by a loose collar G, which has diametrically-opposite offsets z, and is held on said section E by the guide-pieces H, as best shown in Figs. 7 and 8. The said guide-pieces are connected in a fixed manner to the inner side of the section E and are provided at their inner ends with inwardly-directed arms a', recessed as shown. They are also slotted, as indicated by b', and are provided at their outer ends with outwardly-directed arms c', for a purpose presently described.

I is the drill-rod, which is of the ordinary type employed by miners, with the exception that it is provided adjacent to its rear end with a fixed collar d', having lateral arms e' arranged in the slots y of the holder-section E and the slots b' of the guide-pieces H after the manner best shown in Fig. 7, and J (see Fig. 2) is the forward guide of the drill-rod. This forward guide is made up of a fixed member f', connected to the rectangular frame m' and provided with a recess g' and a slot h' and a movable member i', connected in a pivotal manner to the fixed member and recessed at i'. The said movable member is provided with a bearing-box j' to receive a fastener K, which has a lateral arm k' at its lower end designed to take into the slot h' of the member f' and extends upwardly through a slot l' in the upper cross-bar of the frame m' and is provided at its upper end with a handle n'. When the said fastener is rocked in its bearing j', so as to swing its arm k' out of the slot h' of the fixed member f', the movable member i' of the guide J may be drawn upwardly through the medium of the fastener, so as to release the drill-rod.

By reason of the construction just described it will be seen that to remove the drill-rod it is simply necessary to open the forward guide J after the manner stated and turn the collar G on section E until its slotted offsets z are coincident with the slotted arms c' of the guide-pieces H, when the drill-rod may be readily withdrawn from the holder. It will also be observed that with the forward guide J open and the collar G in the position stated the drill-rod may be as readily replaced in the holder and by simply turning the collar G may be secured in its operative position. It will be further observed that by virtue of the provision of the slots y in the holder-section E and the lateral arms e' on the drill-rod I said rod is compelled to turn with the holder-section and yet has a limited endwise movement with respect to the same. The

capability of the drill-rod to move endwise with respect to the holder-section E and the remainder of the machine is highly advantageous, inasmuch as it prevents the transmission of shock and jar to the machine when the rod is struck with a sledge, and thereby materially prolongs the usefulness of the machine.

L is an annular ratchet fixed on the section D of the drill-rod holder.

M is a transverse rock-shaft journaled in the frame m'. N is a coiled spring surrounding said shaft and having one end connected thereto and its opposite end connected to the frame m', and P P' are angular levers fixed at the apices of their angles on the ends of the shaft M, as best shown in Figs. 2 and 4 of the drawings. The depending arms of these levers are connected by rods Q with the collar w on the section E of the drill-rod holder, while the other arm of the lever P is provided with a pawl R (preferably a spring-pressed one) to engage the ratchet L and is designed to be connected by a cord S with a pedal-lever T. The cord may be increased or diminished in length, and hence the pedal-lever may be arranged in the position most convenient for the operator.

In practice my improved drill is fixed in a vertical, horizontal, or inclined position, as desired, through the medium of the screw-points a and the strut or brace B and is operated as follows: The pedal-lever T is first depressed so as to move the section E of the drill-rod holder forwardly and carry the point of the drill-rod to the surface to be drilled and at the same time partially turn the drill-rod holder and the drill. When the point of the drill-rod engages the rock or other substance to be drilled, the arms e' of said rod are moved back to the collar G, as shown in Fig. 4, so that when the rod is subsequently struck with a sledge it is free from the holder and remainder of the machine, and hence no shock or jar is imposed on the holder or other parts of the drill. When pressure is removed from the pedal-lever T, the spring F operates to return the section E of the drill-rod holder, the drill-rod, and the levers P P' to their first positions. In the event of the drill-rod sticking in the hole that is being drilled the spring N, which is compressed by the depression of the pedal-lever and the rocking of the levers P P' and shaft M in the direction indicated by the arrow, tends to expand, and thereby rocks the shaft M and levers P P' in the direction opposite to that indicated by the arrow, the slots in the rods q permitting of such movement of the levers independent of the section E of the holder. Then by simply depressing the pedal-lever T one or more times the operator is enabled through the lever P, pawl R, and ratchet L to partially turn the drill-rod holder and drill-rod and thereby readily free the latter, when the ordinary operation of the drill may be resumed.

V is a dog, which is connected to the frame

m' and arranged to engage the ratchet *L* in such manner as to hold the drill-rod holder against retrograde rotary movement.

The carrier *C* is adjustably fixed on the support *A* by a set-screw *W* and may therefore be moved forward or backward on the support, as occasion demands.

It will be readily appreciated from the foregoing that my improved drill is simple, compact, and strong and that by virtue of the operator being enabled to turn the drill-rod with his foot both of his hands are left free to wield the sledge used in driving the drill-rod, which is an important advantage.

15 I have entered into a specific description of the construction and relative arrangement of the parts embraced in the present embodiment of my invention in order to impart a full, clear, and exact understanding of the same. I do not desire, however, to be understood as confining myself to such specific construction and arrangement of parts, as such changes or modifications may be made in practice as fairly fall within the scope of my 25 claims.

When desirable, an angle-lever *P*², such as shown in Fig. 12, may be employed in lieu of the lever *P*. Said lever *P*² is designed to be fulcrumed at the apex of its angle on one end 30 of shaft *M* and have its depending arm connected to one rod *Q*. It also has its rearwardly-extending arm equipped with a pawl *R* and provided with lateral and curvilinear apertured branches *a*⁷. On this rearwardly-extending arm of the lever *P*² is fulcrumed a lever *a*⁸, which is connected at one end to the cord *S*, leading to the pedal-lever, and has its opposite end adjustably connected by a removable pin *a*⁹ to one of the apertured 40 branches *a*⁷ of the angle-lever. By virtue of this it will be observed that the lever *a*⁸ may be set at various angles to the rearwardly-extending arm of the angle-lever *P*², so as to enable the depression of the pedal-lever to rock said angle-lever when the machine is being used in an upright or approximately upright position.

Having thus described my invention, what I claim is—

50 1. In a rock-drill, the combination of a suitable support, a drill-rod holder mounted on the support and movable endwise with respect thereto, a spring interposed between the holder and support for cushioning the forward movement of the former and returning it to its normal position subsequent to such movement, and a drill-rod arranged in the holder and having a limited endwise movement with respect thereto, whereby it is enabled to move endwise in the holder precedent to the movement of said holder against the tension of the spring, substantially as set forth.

65 2. In a rock-drill, the combination of a suitable support, a rotatable and endwise-movable drill-rod holder, a spring interposed between the holder and support, and a drill-rod

arranged in said holder so as to turn therewith and having a limited endwise movement with respect thereto, whereby it is enabled to move endwise in the holder precedent to the movement of said holder against the tension of the spring.

3. In a rock-drill, the combination with a rotatable drill-rod holder comprising a tubular section held against endwise movement, an endwise-movable tubular section arranged in and connected to the first-named section so as to turn therewith and move endwise with respect thereto and having longitudinal slots; and a coiled spring surrounding the endwise-movable section and interposed between an abutment thereon and the first-named section; of a drill-rod arranged in the holder and having lateral arms arranged in the slots in the endwise-movable section thereof, substantially as specified.

4. In a rock-drill, the combination with a rotatable drill-rod holder comprising a tubular section held against endwise movement, an endwise-movable tubular section arranged in and connected to the first-named section so as to turn therewith and move endwise with respect thereto and having longitudinal slots, slotted guide-pieces connected to said endwise-movable section of the holder and having inwardly-directed and recessed arms at their inner ends and outwardly-directed arms at their outer ends, and a collar loosely mounted on said endwise-movable section and having offsets; of a drill-rod arranged in the holder and having lateral arms arranged in the slots in the endwise-movable section thereof and also in the slots of the guide-pieces, substantially as specified.

105 5. In a rock-drill, the combination with a rotatable drill-rod holder comprising a tubular section held against endwise movement, an endwise-movable tubular section arranged in and connected to the first-named section so as to turn therewith and move endwise with respect thereto and having longitudinal slots, slotted guide-pieces connected to said endwise-movable section of the holder and having inwardly-directed and recessed arms at their inner ends and outwardly-directed arms at their outer ends, a collar loosely mounted on said endwise-movable section and having offsets, a guide arranged in advance of the drill-rod holder and comprising a fixed 110 section, a pivoted section and means for securing the pivoted section; of a drill-rod arranged in the holder and the guide in advance of the same and having lateral arms arranged in the slots in the endwise-movable section 115 of the holder, substantially as specified.

120 6. In a rock-drill, the combination of a drill-rod holder, a frame arranged in advance of the holder, a guide arranged in said frame and comprising a member fixed thereto and having a slot, a pivoted member, and a fastener consisting of a rock-shaft journaled in a bearing on the pivoted member and extending through an opening in one of the bars of

the frame and having an angular arm adapted to enter the slot of the fixed member; and an endwise-movable drill-rod held in the holder and extending through the guide, substantially as specified.

7. In a rock-drill, the combination of a horizontal bar, a carriage comprising one or more inner portions mounted on the bar and having lugs at their opposite sides, provided with 10 apertures disposed in the direction of the length of the bar, an outer portion having corresponding apertured lugs at its opposite sides, and removable longitudinal rods extending through the apertured lugs of the 15 inner and outer portions at opposite sides of the bar so as to hold the outer portion against swinging on the inner portion, and a drill-rod holder arranged in the outer portion of the carriage, substantially as specified.

8. In a rock-drill, the combination of a rotatable drill-rod holder comprising a section held against endwise movement and provided with a ratchet, a section connected with the first-named section so as to turn therewith 25 and move endwise with respect thereto, and a spring interposed between the two sections, a drill-rod movable with the endwise-movable section of the holder, a lever, a pawl carried by the lever and adapted to engage the ratchet 30 of the drill-rod holder, a rod connecting the lever and the endwise-movable section of the drill-rod holder and suitable means for operating the lever, substantially as specified.

9. In a rock-drill, the combination of a rotatable drill-rod holder comprising a section held against endwise movement and provided with a ratchet, a section connected with the first-named section so as to turn therewith and move endwise with respect thereto, and a 35 spring interposed between the two sections, a drill-rod movable with the endwise-movable section of the holder, a lever, a pawl carried by the lever and adapted to engage the ratchet of the drill-rod holder, a rod connected to the 40 endwise-movable section of the drill-rod holder and loosely connected to the lever, a spring for moving the lever independent of the endwise-movable section of the holder, and suitable means for rocking the lever, substantially as specified.

10. In a rock-drill, the combination of a suitable support, a rotatable drill-rod holder comprising a tubular section held against endwise movement in the support and having a 55 ratchet, an endwise-movable, tubular section

arranged in the first-named section so as to turn therewith and move endwise with respect thereto, a coiled spring surrounding the endwise-movable section and interposed between the two sections, a drill-rod arranged 60 in the holder, a frame fixed on the support, a rock-shaft journaled in said frame, a coiled spring surrounding said shaft and connected at one end thereto and at its opposite end to the frame, a lever fixed on said shaft, a rod 65 loosely connected to the lever and interposed between the same and the endwise-movable section of the holder, a pawl carried by the lever and arranged to engage the ratchet of the holder, and a pedal-lever connected with the 70 said lever, substantially as specified.

11. In a rock-drill, the combination of a rotatable drill-rod holder comprising a section held against endwise movement and provided with a ratchet, a section connected with the 75 first-named section so as to turn therewith and move endwise with respect thereto, and a spring interposed between the two sections, a drill-rod movable with the endwise-movable section of the holder, an angular lever having a depending arm and a rearwardly-extending arm equipped with a pawl, a rod connected to the endwise-movable section of the drill-rod holder and loosely connected to the lever, a spring for moving the lever independent 80 of the endwise-movable section of the holder, a lever mounted on and adjustably connected to the rearwardly-extending arm of the angle-lever, and means connected to said adjustably-connected lever for rocking the 85 angle-lever, substantially as specified.

12. In a rock-drill, the combination of a rotatable drill-rod holder provided with a ratchet, the rock-shaft M, the spring N, a lever fixed on the rock-shaft equipped with a 95 pawl for engaging the ratchet and having lateral, apertured branches, a second lever fulcrumed on the first-named lever and adjustably connected by means of a removable pin to one of the apertured branches thereof; said 100 second lever being adapted to be connected to a pedal-lever, substantially as specified.

In testimony whereof I have hereunto set my hand in presence of two subscribing witnesses.
